UNITED STATES PATENT OFFICE

JOHN M. STONESTREET, OF MARSHALLTOWN, IOWA.

RETOUCHING-CABINET.

No. 884,535.

Specification of Letters Patent.

Patented April 14, 1908.

Application filed July 15, 1907. Serial No. 383,746.

To all whom it may concern:

Be it known that I, JOHN M. STONESTREET, a resident of Marshalltown, in the county of Marshall and State of Iowa, have invented 5 certain new and useful Improvements in Retouching-Cabinets, of which the following is a full, clear, and exact description.

The invention relates to retouching cabinets.

10 In the art of retouching a retoucher is desirous of having the negative on which the work is being done in a convenient position to avoid becoming tired and for this purpose it is desirable to occasionally set the negative-bed at different angles or to support it at different elevations so the retoucher can frequently and conveniently change his posture and avoid long-continued strains. The retoucher, in cabinets now in use frequently 15 withdraws from the cabinet and ceases work because the air in the cabinet becomes impure as a result of lack of atmospheric circulation in the cabinet from which the light is necessarily excluded while work is being 20 done therein.

25 The invention designs to provide an improved cabinet which can be readily and conveniently adjusted to permit the change of posture of the operator in working to bring 30 the negative in different relative convenient positions.

35 The invention further designs to provide a cabinet which is so constructed that the chamber for the head of the retoucher is ventilated and from which the light is excluded.

The invention further designs to provide 40 a retouching cabinet of improved construction.

The invention consists in the several novel 45 features hereinafter set forth and more particularly defined by claim at the conclusion hereof.

In the drawings: Figure 1 is a perspective 50 of a cabinet embodying the invention. Fig. 45 2 is a longitudinal section thereof. Fig. 3 is a rear view, the hood or top and sides of the cabinet being shown in section. Fig. 4 is a detail of one of the clamps for securing the parts in assigned position. Fig. 5 is an enlarged section on line 5—5 of Fig. 3.

55 The cabinet is mounted in a portable supporting-frame comprising standards 10, mounted on suitable legs 11 which are usually provided with casters to facilitate movement of the frame and a top cross-bar 12 rigidly connected to the standards by brack-

ets 13, and an adjustable cross-connector or bar 14 which is secured in suitable brackets or guides 15 which are slidable on the standards and secured thereto in assigned position 60 by screws 16. In retouching, it is sometimes desirable to move the retoucher's chair between the standards of the supporting-frame. The cross-bar or support 14 may be moved vertically to clear the chair and 65 limbs of the retoucher, said bar being vertically adjustable on the standards to securely connect them so it can be set at any desired elevation, leaving sufficient space below it for the lower portion of the body of the retoucher and the chair as seen more particularly in Fig. 1. The supporting-frame may be formed of wood or metal as preferred, that shown being of metal.

A vertically adjustable cabinet-frame is 70 75 slidably supported by the supporting-frame and comprises stiles 17 arranged between the standards and connected at the top by a bar 18 and at the bottom by a cross-bar 19 to which is secured a shelf or table 20 for holding the materials used by the retoucher. For convenience in adjusting the vertical adjustable cabinet frame it is connected by cables or chains 21 which are trained over sheaves 22, to counter-weights 23 arranged 80 85 in standards 10 of the supporting-frame. These counter-weights hold the retouching-frame and cabinet in assigned elevation and a suitable clamp 24 firmly secures the supporting-frame and cabinet in desired elevation.

The cabinet proper, comprises a front or bed 25, sides 26, and a hood or top 27. At its bottom the cabinet is pivotally connected to the cabinet-supporting frame by spring-hinges 28. The hinges are applied to normally press the cabinet forwardly and a clamp 29 serves to hold the cabinet in such position that the inclination of the bed will suit the convenience of the retoucher. The 100 purpose in providing springs for normally pressing the cabinet forward is to bring the hood as far forward as conveniently possible when the retoucher desires to withdraw from the cabinet and as soon as clamp 29 is released the cabinet will automatically swing forwardly to facilitate withdrawal of the retoucher. The bed of the cabinet by which the negative is supported is tilted about 105 hinges 28 with the cabinet so that the operator can work in different positions. By merely releasing the clamp 29 the cabinet

comprising the bed, hood and sides, may be conjointly shifted, thus avoiding a plurality of adjustments for the hood and the bed. Stops 40 and 41, adapted to contact with the 5 cross-bar 18 of the vertically adjustable frame, restrict the pivotal movement of the cabinet within desired limits.

To provide for ventilation of the cabinet and circulation of air therein to render it 10 more sanitary for the retoucher, the front or bed 25 of the cabinet comprises plural walls 30 having perforations between which a chamber is formed and having perforations 30' therein which are relatively offset to allow 15 the air to pass through the bed and into the chamber within the cabinet without admitting light. The curved hood of the cabinet is also ventilated, being provided with an opening 31 across the top thereof, which is formed 20 between the overlapping ends of the front and rear portions of the top or canopy, thus allowing the air to pass upwardly through the hood without admitting light. The cabinet thus constructed renders the 25 work less tiresome for the retoucher, because of better circulation of air therein.

A substantially square negative-rest or holder 33 is placed in the front or bed of the cabinet, is formed so it fits into a correspondingly shaped opening in the bed or front and is provided with an edge-groove 34 into which fits a projecting ledge 35 of the outer wall of the cabinet-front or bed. A light-opening 36 extends through the negative-board 35 and is eccentrically disposed therein so that the light-opening may be brought into four different positions in the cabinet, to bring the light-opening in such position as the retoucher may desire, *e. g.*, if the retoucher desires 40 to have the light-opening closer to one side of the cabinet than the other, it can be done by withdrawing the negative board and turning it to bring the opening in desired position.

45 A negative-holding bar 38 extends across the inner side of the bed and is held in proximity to the bed by cleats or strips 39 which are spaced from the bed so as to permit the negative supporting-bar 38 to be adjusted vertically or angularly. A clamp 40' of any suitable construction is adapted to secure bar 38 in assigned position. The upper edge of bar 38 is provided with a groove 45 adapted to receive the negative and a similar bar 42 50 is adapted to hold the upper edge of the negative and is slidably held by the cleats 39 so that it can adjust itself according to the size of the negative and the position in which it is held by bar 38.

60 In Fig. 4 is shown a clamp such as may be used for holding the several parts in assigned position. The clamp comprises a bracket 50 which is secured to one of the parts a member 51 slidably mounted in the bracket and 65 a lever 52 pivotally mounted in the bracket

and connected to member 51 by a cam and slot 53.

Manifestly the invention provides a cabinet which is supported so the retoucher can be seated in close proximity thereto and which is vertically adjustable to position the cabinet properly for persons of different heights or to vary the elevation of the cabinet to suit the convenience or disposition of the retoucher and which is ventilated to supply air to the interior of the cabinet in which the head of the retoucher is located and which admits ready adjustment of the slant or angle of the negative bed.

The invention is not to be understood as 80 restricted to the precise details shown and described since these can be modified without departing from the spirit and scope of the invention as set forth in the claims.

Having thus described the invention, what 85 I claim as new and desire to secure by Letters Patent, is:

1. In apparatus of the class described, the combination of a supporting-frame comprising a pair of standards, a cross-connection 90 near the top thereof, a cross-bar for the lower portion of and adjustably connected to the standards so it may be raised or lowered to connect the standards at different elevations, a retouching-cabinet between the standards and a pivotal connection for the cabinet supported by said frame.

2. In apparatus of the class described, the combination of a supporting-frame comprising a pair of standards, legs for said standards, a cross-connection near the top thereof, a cross-bar for the lower portion of and adjustably connected to the standards so it may be raised or lowered to connect the standards at different elevations, a retouching-cabinet between the standards and a pivotal connection for the cabinet supported by said frame.

3. In apparatus of the class described, the combination of a supporting-frame comprising standards, a retouching-cabinet between 110 the standards, a vertically adjustable cabinet-supporting frame sustained by said standards, and a pivotal connection between said cabinet-supporting-frame and the cabinet.

4. In apparatus of the class described, the 115 combination of a supporting-frame comprising standards, a retouching-cabinet between the standards, a vertically adjustable cabinet-supporting-frame slidably connected to the standards, means for locking the frame to the 120 standards, and a pivotal connection between said adjustable frame and the cabinet.

5. In apparatus of the character described, the combination of a supporting-frame comprising a pair of standards, a cabinet-supporting frame comprising a lower cross-bar, an upper cross-bar, and stiles connecting said cross-bars, said frame being vertically adjustable along the standards, and a retouching-cabinet pivotally connected at its lower 130

- end to said vertically adjustable frame and disposed between said side bars.
6. In apparatus of the character described, the combination of a supporting-frame comprising a pair of standards, a cabinet-supporting frame comprising, a lower cross-bar, an upper cross-bar, and stiles connecting said cross-bars, said frame being vertically adjustable along the standards, a retouching-cabinet pivotally connected at its lower end to said vertically adjustable frame and disposed between said stiles, and means for securing the cabinet against pivotal movement.
7. In apparatus of the character described, the combination of a supporting-frame comprising a pair of standards, a cabinet-supporting-frame comprising, a lower cross-bar, an upper cross-bar, and stiles connecting said cross bars said frame being vertically adjustable along the standards, a retouching-cabinet pivotally connected at its lower end to said vertically adjustable frame and disposed between said stiles, means for locking the cabinet against pivotal movement in said cabinet-frame, and means for locking the vertically adjustable frame to the standards.
8. In apparatus of the character described, the combination of a supporting-frame comprising standards, a top bar extending between the standards, a vertically adjustable cabinet-supporting-frame connected to said standards, a retouching-cabinet comprising a bed, a hood and sides, a pivotal connection between said vertically adjustable frame and the cabinet and counter balancing-means connected to said cabinet supporting-frame.
9. In apparatus of the class described, the combination of a supporting-frame comprising standards, a top bar between said standards, a vertically adjustable cabinet supporting frame connected to said standards, means for locking said frame to said standards, counter-weights connected to said cabinet-supporting frame and disposed in said standards, and a retouching-cabinet comprising a bed and a hood pivotally connected to said cabinet supporting frame.
10. In apparatus of the character described, the combination of a supporting-frame comprising standards, a cross-bar at the top thereof and a lower cross-bar adjustably connected to the standards, a cabinet supporting frame slidably connected to the standards, and a retouching cabinet pivotally connected to said cabinet-frame.
11. In apparatus of the character described, the combination of a cabinet comprising a front or bed having ventilating openings therein arranged to exclude the light, a hood and sides and supporting-means for the cabinet.
12. In apparatus of the class described, the combination of a cabinet comprising a front or bed, a hood having a ventilating opening therein arranged to exclude the light, and sides and supporting-means for the cabinet.
13. In apparatus of the character described, the combination of a cabinet comprising a front or bed, a hood and sides, said bed and said hood having ventilating openings therein which exclude the light, and supporting-means for the cabinet.
14. In apparatus of the character described, the combination of a cabinet comprising a front or bed, a hood and sides, said bed and hood having ventilating openings therein which substantially exclude the light, and a supporting-frame to which the cabinet is pivotally connected.
15. In apparatus of the class described, the combination of a supporting-frame comprising standards, a vertically adjustable cabinet, a supporting-frame connected to said standards, a cabinet pivotally connected to said cabinet-frame, said cabinet having ventilating openings therein which substantially exclude the light.
16. In apparatus of the character described, the combination of a cabinet comprising a hood, a bed or front and sides, a negative-rest mounted in said bed and having an eccentrically disposed light-opening therein and removably connected to the bed so the opening can be differentially positioned in the bed, and supporting-means for the cabinet to which it is pivotally connected.
17. In apparatus of the character described, the combination of a cabinet comprising a bed or front, a hood and sides, said front having a light-opening therein, cleats at the sides of said bed, negative holding-bars guided by said cleats, and means for clamping said bar to the cabinet and supporting-means to which the cabinet is pivotally connected.
18. In apparatus of the class described, the combination of a supporting-frame, a retouching-cabinet comprising a bed, sides, and a hood pivotally connected to said frame, means for locking the cabinet against pivotal movement, and a spring shifting the cabinet forwardly about its pivot when the locking-means is released.

JOHN M. STONESTREET.
